UNITED STATES PATENT OFFICE.

WILLIAM HENRY HUSSEY, OF MOUNT VERNON, NEW YORK, ASSIGNOR TO KAUFMANN & STRAUSS CO., OF NEW YORK, N. Y., A CORPORATION OF NEW YORK.

DESIGN FOR A DISPLAY-STAND.

48,786.

Specification for Design.

Patented Mar. 28, 1916.

Application filed November 15, 1915. Serial No. 61,697. Term of patent 3½ years.

To all whom it may concern:

Be it known that I, WILLIAM H. HUSSEY, a citizen of the United States, residing at Mount Vernon, in the county of Westchester and State of New York, have invented a new, original, and ornamental Design for Display-Stands, as shown in the accompanying drawing and described in the following specification.

The drawing shows a perspective view of the display stand showing my design.

I claim:

The ornamental design for a display stand as shown.

WILLIAM HENRY HUSSEY.
